UNITED STATES PATENT OFFICE.

LESTER WITTENBERG, OF NEW ROCHELLE, NEW YORK, ASSIGNOR TO THE BARRETT COMPANY, A CORPORATION OF NEW JERSEY.

ROOFING STRIP.

Application filed July 12, 1923. Serial No. 650,979.

This invention relates to a roofing strip and the process of making the same. It relates more particularly to a roofing strip of the type having a base of fibrous material which is saturated with waterproofing material and coated with plastic material upon which wear-resisting material may be applied. The invention will be understood from the description in connection with the accompanying drawings, in which—

Fig. 1 is a plan view of the strip;
Fig. 2 is an end view of the same;
Fig. 3 is an end view of the same showing the strip folded; and

Fig. 4 is a perspective view showing its appearance when installed upon a roof.

In the drawings, reference character 1 indicates a sheet of roofing material which may comprise a so-called felt base or may be made from fibrous material on an ordinary paper making machine. This base is saturated with waterproofing material such as tar or the like and is provided with a scored line 2 or a series of perforations longitudinally of the strip and preferably nearer one edge than the other. Along one edge of the strip a layer of plastic material 3 such as asphalt or the like may be applied and on this layer, mineral wear-resisting material 4 such as crushed stone, slate, grit or other suitable material may be applied and pressed therein so as to be retained, the extent of the plastic material 3 and mineral surfacing 4 extending to the line 5. A similar layer of plastic material 6 is applied along the other edge and on the other side of the strip having mineral surfacing material 7 applied thereto and the plastic material 6 with the mineral surfacing material 7 extending to the line 8. Slots 9 may be cut along one edge to form tabs and similar slots 10 may be cut along the other edge but staggered with respect to the slots 9.

The strip, after being formed, may be rolled up in a roll longitudinally of the strip and when it is intended to install the same the roll is unrolled and spread horizontally along the roof deck and fastened down in any suitable manner, as, for example, by nails applied at intervals as shown at 11, Fig. 1. The upper portion of the strip is then folded downwardly so that the lower ends of the slots 10 are even with the upper ends of the slots 9. The next strip is applied in a similar manner with the lower

ends of the slots 9 or the tabs formed thereby even with the upper ends of the slots 10 of the strip first applied and offset with respect thereto so that the strips will simulate the appearance of individual shingles as clearly indicated in Fig. 4.

The scoring 2 or perforations or a weakened line formed in any other convenient way will be made in such a position that the strip can be conveniently and readily folded so as to bring the tabs on the respective edges into proper relation with each other. It is preferable that the mineral surfacing material 4 and 7 on the respective sides should be slightly wider than twice the length of the slots 9 and 10 although this is not absolutely necessary. The mineral surfacing material on the two respective edges may be of different sorts or of different colors in order to obtain a more variegated color effect if desired and instead of having slots 9 and 10 corresponding spaces may be provided with contrasting mineral surfacing material or the slots may be omitted entirely and markings corresponding to the slots may be made by pressing a hot instrument against the stone surfacing to cause the plastic material underneath to strike through and thereby produce the effect of tabs along the edges, or the equivalent of tabs may be produced in various other ways such, for example, as by slots, punchings or markings or combinations of the same in various patterns so that varying and various designs may be produced.

I claim:—

1. A roofing strip having mineral surfacing material along one edge on one side and along the other edge on the other side and being adapted to be folded along a longitudinal line nearer one edge than the other so as to bring said mineral material all on one side of the folded article but in different courses.

2. A roofing strip having mineral surfacing material along one edge on one side and along the other edge on the other side and having a row of perforations intermediate its edges along which the shingle may be folded to present the mineral surfacings to the weather in different courses.

3. A roofing strip having mineral surfacing material along one edge on one side and along the other edge on the other side and being weakened along a longitudinal line

nearer one edge than the other so that it may be folded along said longitudinal line to present mineral surfacings to the weather in different courses.

5. 4. A roofing strip having mineral surfacing material along one edge on one side and along the other edge on the other side and being weakened along a longitudinal line

nearer one edge than the other so that it may be folded along said longitudinal line, said strip having spaced tabs along its edges staggered with respect to each other, the strip when folded presenting mineral surfacings to the weather in different courses.

In testimony whereof I affix my signature.
LESTER WITTENBERG.
